CLAIM

The ornamental design for the foot and leg support device for a chair, as shown and described.

DESCRIPTION

FIG. 1 is a perspective view of the foot and leg support device for a chair;

FIG. 2 is a front view of the foot and leg support device for a chair of FIG. 1;

FIG. 3 is a rear view of the foot and leg support device for a chair of FIG. 1;

FIG. 4 is a left side view of the foot and leg support device for a chair of FIG. 1;

FIG. 5 is a right side view of the foot and leg support device for a chair of FIG. 1;

FIG. 6 is a top view of the foot and leg support device for a chair of FIG. 1;

FIG. 7 is a bottom view of the foot and leg support device for a chair of FIG. 1; and,

FIG. 8 is a perspective view of the foot and leg support device for a chair of FIG. 1 shown with environment.

The portions shown in broken lines do not form part of the design.

1 Claim, 6 Drawing Sheets
